UNITED STATES PATENT OFFICE.

AUTHUR E. LE GARE, OF ST. LOUIS, MISSOURI, ASSIGNEE TO COMMONWEALTH STEEL COMPANY, OF ST. LOUIS, MISSOURI, A CORPORATION OF NEW JERSEY.

LOCOMOTIVE BED.

Application filed March 31, 1925. Serial No. 19,632.

This invention relates to new and useful improvements in locomotive construction, the objects being to provide a locomotive bed having improved longitudinal members which greatly strengthen said members particularly at points adjacent to the pedestal openings and which permit placing the driver springs directly on top of the driver boxes, thereby dispensing with the use of driver 10 spring saddles and providing a more compact construction.

With these and other objects in view, my invention consists in certain novel features of construction and arrangement of parts, 15 hereinafter more fully described and claimed, and illustrated in the accompanying drawings, in which—

Figure 1 is a top plan view of my improved locomotive bed.

Figure 2 is a fragmental side elevational view of same.

Figure 3 is a vertical cross section taken on line 3—3 of Figure 1.

Figure 4 is a longitudinal cross section 25 through one of the longitudinal members of the bed and showing the driving spring and the journal box operatively arranged therein.

Figure 5 is a vertical cross section taken on line 5—5 of Figure 4.

Referring by numerals to the accompanying drawings, 10 indicates a locomotive bed having side or longitudinal members 11 united together at spaced intervals by transverse members 12 and end members 13.

Each longitudinal member comprises a pair 35 of vertically disposed spaced wall portions 14 and 15 forming the outer and inner wall members, respectively, united together at appropriate points by horizontally disposed portions 16.

Integrally formed with each longitudinal member 11 and arranged in pairs are pedestal jaws 17 between which are adapted to be operatively arranged driver journal boxes 18 as shown in Figure 4.

The inner wall member 15 has formed integral with its upper edge an inwardly presented and horizontally disposed flange 19 which extends between and is united to the respective transverse members 12. Where

50 the wall member 15 bridges the journal box opening A as formed by pedestal jaws 17, said wall member is offset inwardly as indicated at 21 and is formed with an extension 22 which depends a suitable distance below

55 the top of said opening and is preferably

thickened as indicated at 23, thereby increasing the strength of the longitudinal member at this particular point. The lower edge of each extension 22 has formed integrally therewith an inwardly and horizontally disposed flange 24, the edge of which is turned upwardly as indicated at 25. The ends of each flange 24 merge with the vertically disposed walls 12^a of the respective transverse members 12.

The space between the vertically disposed wall members 14 and 15 is left open, thereby permitting the location of a driver spring 26 in said space directly on top of a driver journal box 18, and the ends of each spring 70 are in operative engagement with the usual spring hangers 27. In this manner, both the driver springs, as well as the spring hangers, are located in recesses or pockets formed by vertical wall members 14 and 15 and are 75 disposed below the top line of longitudinal members 11, thereby providing a more compact construction.

I claim:

1. In a locomotive bed, a longitudinal 80 member having spaced vertically disposed wall members, one of which is offset laterally at a point adjacent to the journal box opening and extends below the top thereof.

2. In a locomotive bed, a longitudinal 85 member having spaced vertically disposed wall portions, the inner one of which is offset laterally at a point adjacent to the journal box opening and extends below the top, and a horizontally disposed reinforcing 90 flange formed integral with said extended wall portion.

3. In a locomotive bed, longitudinal members having spaced vertically disposed wall members, one of which is offset laterally 95 at a point adjacent to the journal box opening and extends below the top thereof, and a horizontally disposed flange formed integral with said laterally offset wall member.

4. A locomotive bed comprising longitudinal members having vertically disposed wall portions disposed above the journal box openings, the inner wall portions extending below the tops of said journal box openings, transverse members uniting said longitudinal members, and laterally and inwardly disposed reinforcing flanges formed integral with said inner walls of said longitudinal members and with said transverse members.

5. A unitary locomotive bed structure comprising longitudinal members having spaced vertically and longitudinally disposed wall portions arranged above the journal box openings, transverse members uniting said longitudinal members, and horizontally disposed reinforcing flanges formed integral with the inner walls of said longitudinal members, said inner walls having portions offset laterally and inwardly and extending below the tops of said journal box openings.
6. A unitary locomotive bed structure comprising longitudinal members having spaced wall portions arranged above the journal box openings thereof, the inner wall portions being offset inwardly and their lower ends terminating below the tops of the respective journal box openings.
7. A unitary locomotive bed structure comprising longitudinal members having spaced vertically and longitudinally disposed walls arranged above the journal box openings thereof, said inner walls extending below the tops of said journal box openings, transverse members uniting said longitudinal members, and horizontally disposed reinforcing flanges formed integral with said inner walls and said transverse members and extending inwardly from said wall members, said inner walls being offset inwardly at points adjacent to said journal box openings.
8. In a locomotive bed, a longitudinal member having spaced vertically and longitudinally disposed wall portions arranged above the journal box openings thereof and opening thereinto, driver journal boxes arranged in said journal box openings, and driver springs disposed between said spaced wall portions and bearing on the respective driver journal boxes.
9. In a locomotive construction, a longitudinal frame member having vertically and longitudinally disposed spaced wall portions above the journal box opening thereof, a driver journal box operatively arranged in said journal box opening, and a driver spring disposed within the space formed by said spaced wall portions and resting on top of said driver journal box.
10. In a locomotive construction, a longitudinal frame member provided above its journal box openings with vertically and longitudinally disposed recesses opening thereinto for receiving driver springs in direct engagement with the driver journal boxes.
11. In a locomotive construction, a longitudinal frame member provided with jaw pedestals, driver journal boxes in operative engagement with the respective pedestal jaws, and driver springs bearing on said driver journal boxes, said longitudinal member being provided with vertically and longitudinally disposed openings communicating with the upper ends of said journal box opening for accommodating said driver springs.
12. In a locomotive construction, a longitudinal frame member provided with jaw pedestals, driver journal boxes in operative engagement with the respective pedestal jaws, driver springs bearing on said driver journal boxes, said longitudinal member being provided with vertically and longitudinally disposed openings open at their lower ends for accommodating said driver springs, and driver spring hangers entering said opening for engaging respective ends of the driver spring.
13. In a locomotive construction, a longitudinal frame member having spaced vertically and longitudinally disposed walls arranged above the driver journal box opening for providing a vertically disposed driver spring opening communicating with said journal box opening.
14. A locomotive bed frame having longitudinal members provided with vertically and longitudinally disposed spaced wall portions forming a vertically disposed driver spring receiving recess open at top and bottom and opening into the driver journal box opening.

In testimony whereof I hereunto affix my signature this 25th day of March, 1925.

ARTHUR E. LE GARE.
